UNITED STATES PATENT OFFICE.

LESTER A. GRIMES, OF ORANGE, NEW JERSEY.

AUTOMATIC ALARM FOR SPRINKLER SYSTEMS.

1,186,307.

Specification of Letters Patent.

Patented June 6, 1916.

Application filed July 8, 1915. Serial No. 38,795.

To all whom it may concern:

Be it known that I, LESTER A. GRIMES, a citizen of the United States, and a resident of Orange, in the county of Essex and State of New Jersey, have invented a new and Improved Automatic Alarm for Sprinkler Systems, of which the following is a full, clear, and exact description.

This invention relates to fluid distribution systems and has particular reference to automatic sprinkler systems for the protection of buildings from fire. The novel features of the invention, however, are adapted for various applications.

Among the immediate objects of the invention is to provide connections for a water or other fluid pipe whereby an alarm may be given to the superintendent or other official at any distant place when there is an abnormal flow or other condition of the fluid in such pipe.

As applied to the water pipes of sprinkler systems, the primary object is to indicate to the superintendent or other official at said distant point the fact that water is flowing through the pipe and therefore indicating either that there is a break somewhere in the system or that the sprinkler system has become operative by reason of the presence of fire.

A further object of the invention is to provide an attachment of the character indicated for a pipe of any standard size, one portion of the attachment being adjustable to accommodate it to different sizes of pipes.

A still further object of the invention is to provide an automatic alarm attachment that will be operative to indicate a flow of water or other fluid in either direction along the pipe.

Another object of the invention is to provide an alarm apparatus casing which is tamper-proof or so constructed that if the casing be opened by any person, an indication of such fact will be given at the central station. The term central station as used hereinafter will be understood as meaning any office or station at which the alarm or indication is to be given according to the design of the apparatus or system.

With the foregoing and other objects in view, the invention consists in the arrangement and combination of parts hereinafter described and claimed, and while the invention is not restricted to the exact details of construction disclosed herein, still, for the

purpose of illustrating a practical embodiment thereof reference is had to the accompanying drawings, in which like reference characters designate the same parts in the several views, and in which—

Figure 1 is a vertical longitudinal section of the improvement applied to a fluid pipe; Fig. 2 is a horizontal section substantially on the line 2—2 of Fig. 1; Fig. 3 is a vertical transverse section on the line 3—3 of Fig. 2; Fig. 4 is an elevation of the tamper switch; Fig. 5 is a vertical sectional detail on the line 5—5 of Fig. 2; Figs. 6 and 7 are perspective views of two of the elements of the diaphragm chamber; Fig. 8 is a diagram of the electric wiring and contacts; and Fig. 9 is a detail on the line 9—9 of Fig. 1.

Referring now more particularly to the drawings, I show at 10 a pipe for the holding or conveyance of fluid, such as water, for an automatic sprinkler system in buildings, and by the use of the term water, as used hereinafter, I wish to be understood as covering any species of fluid adapted to flow in either direction in said pipe. At any suitable place in the pipe or coupling 11 connecting adjacent sections of pipe, I secure an automatic switch box or casing 12 having an outlet 13 for the electrical connections. For convenience of description, the casing will be understood as being in upright position and connected through its bottom to the pipe. I wish it to be distinctly understood, however, that the device is adapted for perfect operation irrespective of its relation to the vertical. The bottom of the casing has a hub 14 whereby it is connected through screw threads 15 to the upper end of a head 16 of circular form. The head includes a central downwardly projecting shank 17. The head may be secured in any manner to the pipe or coupling 11, but is indicated herein as being connected by means of a thimble 18 tapped into the coupling at 18^a and connected by a flanged collar 19 to the outer end of the thimble, the connection just referred to being made watertight in any suitable manner. The head is provided adjacent the bottom of the casing with a pair of independent chambers 20, and the shank 17 likewise is provided with a pair of ports 21 communicating with the respective chambers 20.

At 22 I show a pair of Pitot tubes having parallel shanks fitted slidably in the ports

21 and having their curved ends extending oppositely from each other and with the centers of the curved ends lying in the axis of the pipe 10. The shanks of the tubes 22 are adjustable longitudinally in the ports 21 so as to adapt the length of the tubes to the radius of the main pipe. The tubes 22 are fixed in position by suitable means such as a set screw 23 acting through one side of the shank 17, and the tubes are locked in fixed relation to each other by means of a lug or band 24 along the shanks thereof adjacent the curved ends.

15 Within the casing 12 are a pair of diaphragm chambers 25 of any suitable form in cross section, but shown herein as substantially cylindrical and each having one closed or sealed end and having its open end fitted with a diaphragm 26 whereby the otherwise open end is sealed or closed. The chambers 25 are arranged with their axes parallel and horizontal and are rigidly connected to the bottom of the casing. The 25 interiors of the chambers are in communication through ports 27 with the respective chambers 20. It will appear, therefore, that the inner surfaces of the diaphragms 26 and the chambers 25 will always be subjected to the static pressure of the water in the pipe 10, and such static pressure will always be the same in both chambers 25.

At 28 are fixed spaced contacts connected to a wire 29 leading to a battery B.

35 30 indicates a movable contact between the fixed contacts 28 and adapted to engage with either of them but normally out of contact with both. The movable contact is connected by a wire 31 to the battery 30 through an alarm device indicated as a bell 32 at any desired place. The movable contact 30 is carried by a compound lever mechanism shown best in Figs. 2 and 3. This mechanism comprises a T-shaped 45 rocker 33 pivoted at 34 on a post 35 extending upwardly from the bottom of the casing. The shank of the rocker 33 carries a pin 36 acting in a slot 37 of a second lever 38 pivoted at 39 on a post 40 on the opposite side of the casing. The lever 38 at its free end carries a pin 41 acting in the slot 42 of a third lever 43 pivoted at 44 on the pivot 34 coaxially with the rocker 33. The free end of the last mentioned 55 lever 43 carries a block of insulation 45 to which is connected the movable contact 30. The points 33' of the rocker are associated with the respective diaphragms 26 by the means shown best in Fig. 5, and including 60 for each diaphragm a knuckle 46 pivoted at 47 on the adjacent point 33' and having an axially arranged stem 48 adjustably tapped into the knuckle at one end and carrying a disk 49 at its other end carried by or abutting against the outer surface of

the adjacent diaphragm. The stems 48 of these connections may be delicately adjusted so as to cause the normal static pressure in the chambers 25 to hold the movable contact 30 in mid position free from the fixed contacts 28, and such adjustment may be made permanent or secure by lock nuts 50.

70 From the structure set forth, it follows that if the pressures in the two chambers 25 against the inner surface of the diaphragms become unbalanced from any cause, the rocker 33 will be moved on its pivot, and such movement, though of slight extent, being multiplied through the other levers 38 and 43, will cause the movable contact 30 to engage one or the other of the fixed contacts 28, thereby closing the circuit and ringing the alarm bell 32.

75 51 indicates another pair of spaced fixed contacts adjacent the contacts 28 and adapted to be engaged individually by a movable contact 52 carried by the block of insulation 45, this action being similar to that described in connection with the contacts 28 and 30. The fixed contacts 51 are connected to a wire 53 and the movable contact 52 is connected to a wire 54, these wires constituting a circuit for a special instrument as, for instance, a transmitter. At 55 and 56 are fixed and movable contact springs, one 80 being connected to a wire 57 and the other to said wire 53. The wires 53 and 57 constitute what may be termed a tamper circuit, and the springs 55 and 56 are normally in contact with each other, being so held by a 100 lug 58 carried by the cover 59 of the casing. When the casing is opened by releasing the lock 60 and screws 60', the circuit 53, 57 is broken by the separation of the contact springs. Any person at the central station, 105 therefore, will be advised immediately that some one is tampering with the mechanism. If, however, an authorized person opens the casing, he may again close the circuit even though the casing is left open for inspection or repairs, by means of a dog 61 pivoted at 62 adjacent the spring 55 and adapted to be held elevated, as shown in Fig. 4, by a catch 63 constituting a part of the contact spring 56. The dog in this position bridges the 110 space between the contact springs and thereby closes the circuit. The dog, however, extends into the path of the lug 58 and is automatically disconnected from the catch 63 when the casing is again closed, the lug 58 115 turning the dog downwardly around its pivot 62.

120 The several wires and circuit connections described above may be variously arranged, suitable binding posts being employed to 125 make the connections.

The instruments not constituting any part of the present improvement are not shown.

130 As above premised, the normal pressure of the water in the pipe 10 is communicated

through the tubes 22, ports 21, chambers 20, and ports 27, to the diaphragm chambers 25, and the diaphragms are normally adjusted so that such normal pressure will serve to hold the movable contacts 30 and 52 in mid position between their respective fixed contacts 28 and 51 respectively. If, however, there be an opening anywhere in the pipe system it will occasion a flow of water in the pipe as, for instance, in the direction of the arrow on Fig. 1, the normal static pressure in the diaphragm chamber 25 communicating with that tube having its inlet pointing in a direction opposite to the direction of flow of water will be augmented by the pressure incident to the flow, while in the opposite diaphragm chamber the normal static pressure will be diminished by the suction or injector action in the direction of the flow. This causes, therefore, an unbalancing of the pressures in the two diaphragm chambers; with the result that one of the diaphragms will cause the rotation of the rocker and the movement of the contacts 30 and 52 into engagement with one or the other of the fixed contacts of both sets, causing the bell 32 to ring and a corresponding action through the circuit 53, 54.

It frequently occurs that the water in the pipe is caused to move in an abrupt manner causing a sort of hammer. In order to avoid the difficulty resulting from such irregularity of flow with a corresponding sudden or irregular vibration of the diaphragms, I arrange in each of the chambers 25 a multiplicity of plates 58^a and 58^b each having a peripheral flange 59. These plates are shown as circular to correspond with the cross sectional form of the diaphragm chambers. Each flange 59 is adapted to receive the next adjacent plate and provides a clear space between the main portions of adjacent plates. The plates 58^a are each provided with a single hole 58', and the other plates 58^b are each provided with a plurality of holes 58''. The holes of adjacent plates are staggered with respect to one another; that is to say, the hole 58' in the plate 58^a being the center will always be out of alignment with both of the holes 58'' irrespective of any thought of the operator as to circumferential adjustment or position. In other words, the multiplicity of plates in each chamber 25 constitutes a labyrinth through or along which the fluid pressure is transmitted slowly or gradually and hence overcomes the undesirable rapid vibration of the diaphragms due to sudden impulses in the current of water.

It will be observed that the signal apparatus is designed to be connected directly to any water or other fluid pipe and is operative directly from the current in the pipe in either direction and without the trouble or expense of providing mechanism having

either a bypass or a check valve. It is noteworthy, too, that the apparatus does not depend in any manner for its operation upon a circulation of fluid through it, the result being obtained by varying pressures only. 70

I claim:—

1. In a device of the character set forth, the combination of a pair of independent pressure chambers each having a diaphragm serving to close the same, means to supply variable fluid pressures to the respective chambers from either direction to act upon the inner surfaces of said diaphragms, and movable contact devices adjacent the chambers set in operation by the unbalancing of the pressures in said chambers irrespective of the direction in which the excess of pressure is applied. 75

2. In a device of the character set forth, the combination of a pair of independent pressure chambers, a pair of diaphragms closing said chambers, means to apply fluid pressure in variable degrees into said chambers, a pair of contacts adjacent the chambers, a T-shaped rocker adjacent the diaphragms, and speed multiplying devices between said contacts and said rocker whereby a slight movement of one of the diaphragms due to unbalancing of the pressures in the chambers will cause an effective movement relatively at the contacts. 85

3. In a device of the nature set forth, the combination of a pair of cylindrical diaphragm chambers having their axes parallel to each other, means to introduce pressure fluid into the chambers independently of each other, a pair of diaphragms closing the ends of the chambers, a rocker pivoted adjacent the diaphragms and having an extension between the chambers, connections between the points of the rocker and the diaphragms and serving to hold said extension in mid position, a pair of electrical contacts, and means between said rocker extension and the contacts to make the contacts functional upon a slight movement of the rocker. 100

4. In a device of the character set forth, the combination of a casing, a pair of pressure chambers within the casing, diaphragms connected to the chambers closing the same, a movable member having ends adjacent the chambers, connections between the ends of the movable member and the diaphragms, a plurality of pairs of contacts, compound lever mechanism between the movable member and the contacts, said lever mechanism carrying one contact of each pair, said pairs of contacts being made functional by the movement of the member, and means to introduce a pressure fluid into said chambers. 110

5. The combination with a support, of a casing, a circular head connected to the casing and having a pair of chambers therein and also having a shank extending toward the support, means surrounding the shank 120

- serving to connect the casing and head to the support, said shank having a pair of ports communicating individually with said head chambers, a pair of diaphragm chambers 5 within the casing communicating with the respective head chambers, means to convey pressure fluid to said shank ports, and a series of contacts made operative by variation in pressures in the pairs of pressure chambers.
6. In a device of the character set forth, the combination of a casing, contacts therein, a pair of diaphragm chambers, movable connections between the diaphragms and said

contacts made functional by variations in 15 pressures in said chambers, a pipe, means to connect the casing to the pipe, and tubular connections between the pipe and the chambers aforesaid, said connections including a pair of tubes adjustable with respect to the 20 pipe whereby their open ends may be positioned in the axis of the pipe irrespective of the diameter of the pipe, and means to lock the tubes in adjusted position.

LESTER A. GRIMES.
